United States Patent Office

Des. 212,311
Patented Sept. 24, 1968

212,311

CALCULATING MACHINE

Carl Auboeck, Vienna, Austria, and Wolfgang Bindel,
Wilhelmshaven, Germany, assignors to Olympia Werke
AG, Wilhelmshaven, Germany

Filed Dec. 26, 1967, Ser. No. 9,923

Claims priority, application Germany Oct. 5, 1967

Term of patent 14 years

(Cl. D64—11)

Fig. 1

Fig. 2

Fig. 3

FIG. 1 is a perspective side view of a calculating machine showing our new design;

FIG. 2 is a perspective front view; and

FIG. 3 is a perspective rear view of our design.

The essential features of our design reside in the portions shown in solid line; conventional keys being shown in broken lines in all the views.

We claim:

The ornamental design for a calculating machine, substantially as shown and described.
